UNITED STATES PATENT OFFICE.

WALTER E. HUENEFIELD, OF CINCINNATI, OHIO, ASSIGNEE TO THE HUENEFIELD COMPANY, OF CINCINNATI, OHIO.

HYDROCARBON-BURNER.

1,110,786.

Specification of Letters Patent. Patented Sept. 15, 1914.

Application filed October 10, 1912. Serial No. 724,971.

To all whom it may concern:

Be it known that I, WALTER E. HUENEFIELD, a citizen of the United States, residing at Cincinnati, in the county of Hamilton and State of Ohio, have invented certain new and useful Improvements in Hydrocarbon-Burners; and I do hereby declare the following to be a full, clear, and exact description of the invention, such as will enable others skilled in the art to which it appertains to make and use the same.

This invention relates to improvements in hydro-carbon burners and more particularly to such as are adapted for use with oil stoves,—the object of my present invention being to provide simple and efficient means for supporting the combustion chamber member upon the wick tube member and to so construct a part of the combustion chamber member as to afford an effective limiting device for the wick.

With this and other objects in view, the invention consists in certain novel features of construction and combinations of parts as hereinafter set forth and pointed out in the claims.

In the accompanying drawings, Figure 1 is a sectional view of the device with the parts in their normal operative positions. Fig. 2 is a view showing the parts forming the combustion chamber in elevated position; Fig. 3 is a transverse sectional view on the line $x-x$ of Fig. 1; Fig. 4 is a transverse sectional view on the line $y-y$ of Fig. 1; Fig. 5 is a perspective view showing one member of the raising and lowering devices, and Fig. 6 is an enlarged fragmentary sectional view, showing the mounting of the combustion chamber member upon the wick tube member.

1 represents the wick tube member and 2 the combustion chamber member of the burner. The wick tube member comprises concentric tubes 3—4 forming a wick chamber between them to receive a wick 5,—a perforated holder 6 being provided for the latter to coöperate with suitable raising and lowering means.

The outer wick tube is provided at its upper end with an outwardly projecting depressed flange or seat 7, and the inner wick tube is provided at its upper end with an inwardly projecting flange 8, from the inner

edge of which, a ring 9 projects upwardly. From the upper edge of said ring, an annular flange or seat 10 projects inwardly and may be provided at its inner edge with a depending rib 11.

The combustion chamber member 2 comprises concentric foraminated shells 12—13 spaced from each other to form a combustion chamber 14 between them, which is in line with the wick. The shells are inclosed by a casing 15 which is spaced from the outer shell 13 and is open at its upper end, the lower end of said casing being provided with an inwardly projecting perforated flange 16. The shells 12—13 and casing 15 are secured together by means of cross-rod 17.

The lower end of the shell 13 is seated (when the parts are in their normal working positions) upon the outer depressed flange or seat 7 at the upper end of the wick tube 3. The inner foraminated shell 12 is provided at its upper end with a perforated cap 18 and at its lower end (which terminates a short distance above the horizontal plane of the lower end of the shell 13) is provided with a perforated cap 19 which rests (near its peripheral portion) upon the seat 10 at the upper end of the inner wick tube 4. Thus it will be seen that the foraminated shells of the combustion chamber member are supported respectively, upon the seats 7 and 10 of the wick tube member, with the combustion chamber 14 immediately over and in direct alinement with the wick, and that the weight of the parts will insure the firm seating of said foraminated shells.

The lower cap 19 is constructed with an annular series of radial lugs or fingers 20 and the lower end of the shell 12 is notched to accommodate said lugs or fingers,—the lugs 21 formed by thus notching the lower end of the shell being bent under the edge of the cap 19 and serving to retain the latter in place. The lugs or fingers 20 enter the combustion chamber 14 and project a sufficient distance across the lower portion of the same to be in line with the wick and constitute limiting means for the latter. From this construction, it will be observed that the wick limiting lugs or fingers are made integral with the lower cap of the inner shell

12 and that said lugs or fingers are therefore vertically movable with the combustion chamber member away from and toward the wick, but that when the burner is in operation, said limiting devices may be in more or less proximity to the wick (according to the adjustment of the latter) without detracting from the efficiency of the flame on the wick.

10 A tube 22 is secured at its upper end to the lower cap 19 and, projecting downwardly through the opening formed by the annular flanges 10-11, enters the space within the wick tube member. The tube 22 constitutes a guide for the vertical movements of the combustion chamber member, when the latter is raised or lowered by means of devices such as will now be described.

20 A ring 23 is located within the cylindrical space formed by the inner wick tube and is provided with arms 24 rigidly secured in any suitable manner to the interior of the inner wick tube with a plurality of upwardly projecting arms 25 corresponding in number with a plurality of pins 26 which project inwardly from the wall of the tube 22 near the lower end of the latter. Each arm 25 is provided at one side with a diagonal edge 27 and at the upper end of each diagonal edge, a horizontal seat 28 is formed and at one end of the latter, a lug 29 projects upwardly so as to form a stop shoulder 30. At the side of each arm 25 opposite the diagonal or inclined edge thereof, a horizontal slot 31 is formed,—the lower wall of the horizontal slot in one arm forming, in effect, a continuation of the inclined or diagonal edge of the adjacent arm but at an angle to said edge.

When the combustion chamber member is in its normal operative position, the inwardly projecting pins 26 of the guide tube 22 will be disposed in the horizontal elongated slots 31 of the arms 24 and said combustion chamber member will be locked in its lower operative position. When it is desired to raise the combustion chamber member above the wick tube member, the operator will turn said combustion chamber member in one direction so as to cause the pins 26 to ride on the inclined edges 27 of the arms 25. When the pins 26 shall have reached the upper ends of said inclined edges, a further turning movement of the guide tube will cause said pins to become disposed upon the horizontal seats 28 at the upper ends of the arms 25 and thus the combustion chamber member will be sustained in its elevated position. Engagement of the pins 26 with the stop shoulders 30 will prevent the combustion chamber member and guide tube from being turned too far. It is apparent that by turning the 60 combustion chamber member in the reverse

direction, the pins 26 will be moved off of the horizontal seats 28, and when said pins reach the inclined edges 27 of arms 25, the weight of the combustion chamber member will be sufficient to cause said pins to ride down the inclined edges and enter the elongated slots 31, thus causing the combustion chamber member to become disposed in operative position on the wick tube member and to be locked in such position.

Having fully described my invention what I claim as new and desire to secure by Letters-Patent, is:

1. In a hydrocarbon burner, the combination with a wick tube member, of foraminated shells forming a combustion chamber over the wick tube member, a cap at the lower end of the inner of said shells, a plurality of separated wick limiting devices integral with said cap and normally disposed above the wick tube member and means for raising and lowering the combustion chamber member and the limiting devices carried thereby.

2. In a hydrocarbon burner, the combination with a wick tube member provided with inner and outer seats at the upper end, of concentric foraminated shells above said wick tube member and adapted to rest on said seats, said shells forming a combustion chamber between them, and a cap secured to and forming the bottom of the inner shell, said cap provided on its periphery with a plurality of radial lugs entering the combustion chamber and disposed in the wick path.

3. In a hydrocarbon burner, the combination of a wick tube member comprising concentric tubes, one of said tubes having an outer annular seat at its upper end, and the other tube having an inner elevated annular seat, a combustion chamber comprising concentric foraminated shells forming a combustion chamber, the outer shell adapted to rest on the outer seat of the wick tube member, and a cap secured to the lower end of the inner shell and adapted to rest on the inner elevated seat on the inner tube of the wick tube member, said cap having a plurality of radial fingers projecting outwardly beyond the wall of said inner shell and constituting wick limiting means.

4. In a hydrocarbon burner, the combination with a wick tube member provided at its upper end with an outer flange and with an inwardly projecting flange, of a combustion chamber member comprising concentric shells, the outer of said shells adapted to seat on the outer flange of the wick tube member, a cap rigidly secured to the inner shell, said cap adapted to rest on the inner flange of the wick tube member, a depending tube secured at its upper end to said cap and passing through the opening formed by said inner flange, whereby said

flange and tube will guide the vertical movement of the combustion chamber member, and means within the wick-tube member co-operating with said depending tube for effecting the raising and lowering of the combustion chamber member.

5 In testimony whereof, I have signed this

specification in the presence of two subscribing witnesses.
